Law Office LLC(57) **CLAIM**

The ornamental design for a multilegged work station, as shown and described.

DESCRIPTION

FIG. 1 is a top perspective view of a multilegged work station;
 FIG. 2 is a bottom perspective view of the multilegged work station of FIG. 1;
 FIG. 3 is a top plan view thereof;
 FIG. 4 is a bottom plan view thereof;
 FIG. 5 is a right side elevational view thereof; and,
 FIG. 6 is a front elevational view thereof.

1 Claim, 4 Drawing Sheets(56)
